G. BOWMAR.
PISTON.
APPLICATION FILED DEC. 24, 1920.

Patented Sept. 6, 1921.

FIG. 1.

FIG. 2.

FIG. 3.

INVENTOR
GERSHON BOWMAR.

BY
J. H. Bowmar
ATTYS.

UNITED STATES PATENT OFFICE.

GERSHON BOWMAR, OF TORONTO, ONTARIO, CANADA, ASSIGNOR OF ONE-HALF TO
WILLIAM EDWARD HOLDER, OF TORONTO, ONTARIO, CANADA.

PISTON.

1,390,193.

Specification of Letters Patent.

Patented Sept. 6, 1921.

Application filed December 24, 1920. Serial No. 438,007.

To all whom it may concern:

Be it known that I, GERSHON BOWMAR, a subject of the King of Great Britain, and a resident of the city of Toronto, in the 5 county of York, in the Province of Ontario, Canada, have invented certain new and useful Improvements in Pistons, of which the following is a specification.

My invention relates to improvements in 10 pistons and the object of the invention is to provide a piston characterized by a vacuum space formed in the head end of the piston which will be light, strong and durable and will retain its vacuum indefinitely.

15 To the attainment of the foregoing, the invention consists in the improvement as hereinafter described and definitely claimed.

In the accompanying drawings, forming part of this specification:

20 Figure 1 is a sectional view through my piston and vacuum chamber.

Fig. 2 is a sectional view through a mold showing the vacuum chamber and the metal forming the piston when poured into the 25 mold.

Fig. 3 is a perspective detail of the vacuum chamber shown in Figs. 1 and 2.

In the drawings like characters of reference indicate the corresponding parts in 30 each figure, and for the sake of clearness the piston will be described in connection with a method of making the same which will be claimed in an application divisional of this.

1 indicates a piston. 2 is a vacuum chamber 35 which is formed of sheet metal which is non porous and which is cast within the piston 1 being secured to the core 3 of the mold as indicated in Fig. 2 by wires 4 which are temporarily secured to the inner face of the

40 vacuum chamber 2 and extend into the body of the core. The wall 5 of the vacuum chamber 2 is provided with a punched orifice 6.

It will be noted that the head of the core 3 is slightly smaller in diameter than the 45 diameter of the vacuum chamber 2.

When the metal 7 forming the piston is poured into the mold it forms an annular shoulder 8 around the interior of the piston serving to hold the vacuum chamber 2 in 50 place. The inner wall 5 of the vacuum chamber is also preferably provided with a series of annular corrugations 9 to allow for the expansion and contraction of the metal during heating and cooling. The vacuum cham-

ber 2 is secured by the wires 4 to the core 3 55 of the mold and is then inserted in the mold and the metal 7 poured. When the metal is cooled and the piston removed from the mold and the core removed the piston and vacuum chamber 2 are reheated to a temperature below the fusing point of the metal but sufficient to form a vacuum within the chamber, the expanding air passing out through the perforation 6. The perforation 6 is then sealed as indicated at 10 (see Fig. 65 1) and the piston and vacuum chamber allowed to cool.

It has been found in practice that my construction of piston is the only one by which the vacuum can be retained in a piston without unduly increasing the weight of such piston as it is essential that such vacuum be formed in a chamber of non-porous metal and not formed directly in the piston which being formed of cast metal is porous and for 70 this reason the vacuum is soon destroyed unless the wall of the chamber be made of such a thickness as to make the piston too heavy for practical use.

What I claim as my invention is:

1. In a piston, a piston body having a hollow interior, and a vacuum chamber formed of non-porous metal secured within the piston body so as to cover the interior face of the head thereof.

2. In a piston, a piston body having a hollow interior, a vacuum chamber formed of non-porous metal fitting within the piston so as to cover the interior face of the head, the said piston body having a projecting portion formed in the interior thereof and bearing against the inner face of the chamber to retain it in place.

3. In a piston, a piston body formed with a hollow interior and having an annular interior shoulder cast therearound, and a vacuum chamber fitting between the interior face of the head and the annular shoulder at its edge.

4. In a piston, the combination with a hollow piston body, of a vacuum chamber formed of non-porous material and located in the piston body; the said vacuum chamber being opposed to the inner side of the head of the piston body and being provided with 100 the inner corrugated wall.

5. A piston having therein a chamber in which is a vacuum or partial vacuum; the

said chamber being formed of non-porous material; the said chamber being located adjacent to the head of the piston and having its wall remote from the piston corrugated.

5 6. In a piston, a piston body having a hollow interior and a vacuum chamber formed of non-porous metal secured within the piston body.

10 7. In a piston, a piston body having a hollow interior and vacuum chamber formed of non-porous metal secured within the piston body and constructed and arranged to ex-

pand and contract independently of the contraction and expansion of the piston head. 15

8. In a piston, a piston having a hollow interior and a vacuum chamber formed of non-porous metal secured to the inner side of the head of the piston and having the wall remote from the piston head corrugated to permit expansion and contraction of the vacuum chamber independently of the expansion and contraction of the piston head. 20

GERSHON BOWMAR.
